UNITED STATES PATENT OFFICE.

JOSEPH YATES, OF LONDON, ENGLAND.

STEAM-PACKING.

SPECIFICATION forming part of Letters Patent No. 564,908, dated July 28, 1896.

Application filed October 7, 1895. Serial No. 564,944. (No model.) Patented in England May 3, 1893, No. 8,888; in France April 28, 1894, No. 238,144; in Belgium April 30, 1894, No. 109,725, and in Germany May 20, 1894, No. 81,140.

To all whom it may concern:

Be it known that I, JOSEPH YATES, a subject of the Queen of Great Britain, residing at London, England, have invented a certain 5 new and useful Improved Steam-Packings, suitable for other fluid pressure, (for which I have obtained patents in Great Britain, No. 8,888, dated May 3, 1893; in Germany, No. 81,140, dated May 20, 1894; in France, No. 238,144, dated April 28, 1894, and in Belgium, No. 109,725, dated April 30, 1894;) and I do hereby declare the following to be a full, clear, and exact description of the invention, such as will enable others skilled in the art to which 15 it appertains to make and use the same.

My invention relates to improvements in packing for pistons, and more especially to packing for that class of pistons which reciprocate in a curve; and it consists of the novel 20 features hereinafter described and claimed.

My invention will be understood by reference to the accompanying drawings, wherein the same parts are indicated by the same letters throughout the several views.

25 Figure 1 illustrates a partial sectional side elevation of a piston and its casing with which my improved packing is used. Fig. 2 illustrates an enlarged front elevation of the piston fitted with my improved packing. Fig. 3 30 illustrates a sectional side elevation of the piston shown in Fig. 2; and Figs. 4 and 5 illustrate detail perspective views of the packing-strips, showing the method of joining the same.

35 A represents the casing for the piston, which corresponds to the usual cylinder of a steam-engine.

B represents the piston, which in working moves forward and backward in the casing A 40 from its bottom as a pivotal point, being attached to the shaft or axle C.

H and II represent steam-ports.

J represents a slide-valve, and N represents the exhaust.

45 T represents the piston-packing. This packing consists of angular strips of metal T, which fit together, as shown at T', where it will be seen that each member is provided with a plurality of tongues and grooves, which 50 connect with corresponding tongues and grooves on the opposite member. An angu-

lar plate is fitted over the joint between each pair of members and is attached to one of said members, while it will slide freely upon the opposite member. In this way a slight 55 longitudinal movement of each member will be allowed and the joint will yet remain tight.

The packing-strips T are held in place upon the piston B by means of the flat metal frame 60 T³, which has outwardly-extending lugs or fingers T², which extend across the inner faces of the said packing-strips and hold them in position, as shown most clearly in Fig. 2. The fingers T², however, should bear loosely 65 upon the packing-strips in order to allow the same to spread when steam enters the cylinder behind the piston.

When the piston is at either end of the stroke the steam entering the cylinder through its 70 proper port will cause the various members of the packing-strips to slide outward, due to the pressure of the incoming steam acting upon the side flanges T⁴ of the said packing-strips, and these strips will thus be caused to 75 bear firmly against the inner walls of the cylinder-casing as long as the steam-pressure continues, or, in other words, until the end of the stroke.

When the exhaust takes place, the pressure 80 of the steam being removed from the packing on the return stroke, the packing on the exhaust side will come back practically free from the inside of the cylinder-casing, as there will be no great amount of pressure 85 upon the side flanges T⁴ to expand it. It will be understood that this arrangement of packing is on each side of the piston, and that when the engine is working the packing on the two sides of the piston will be expanded 90 alternately, according to which side of the piston the steam is acting upon.

It will be seen that I provide a simple and effective packing which is suitable for many kinds of pistons and which requires no springs 95 or other mechanical means to make said packing effective when in use.

Having thus described my invention, what I claim, and desire to secure by Letters Patent of the United States, is—

1. The combination, with a piston of the character described, of a packing composed

of a plurality of angular metal packing-strips T^4 having side flanges T^4 , and each provided with a plurality of tongues and grooves which register with corresponding tongues and grooves on the adjacent strip, and allow of longitudinal motion; and a metal frame secured to each side of said piston and having outwardly-extending lugs or fingers thereon which bear loosely upon said packing-strips, and hold the same in position, substantially as described.

2. The combination, with a piston of the character described, of a packing composed of a plurality of angular metal packing-strips T^4 having side flanges T^4 , and each provided

with a plurality of tongues and grooves which register with corresponding tongues and grooves on the adjacent strip; an angular plate attached to one of said strips at each junction and covering the same on the inner 20 sides of the said strips; a metal frame secured to each side of said piston, and lugs or fingers on said frame which fit over and bear loosely upon said packing-strips, and hold the same in position, but allow of their expansion 25 and contraction, substantially as described.

JOSEPH YATES.
